Jacques Guerin, Puteaux, France, assignor to
D'Orsay Perfumeries Corporation, New York,
N. Y., a corporation of New York

Application January 23, 1948, Serial No. 144,001

Term of patent 14 years

(Cl. D58—8)

To all whom it may concern:

Be it known that I, Jacques Guerin, a citizen of France, residing at Puteaux, France, have invented a new, original, and ornamental Design for a Bottle, of which the following is a specification, reference being had to the accompanying drawing, forming part thereof.

In the drawing:

Fig. 1 is an elevational view of a bottle, showing my new design;

Fig. 2 is a top plan view thereof, and

Fig. 3 is a bottom plan view thereof.

I claim:

The ornamental design for a bottle, substantially as shown.

JACQUES GUERIN.
